C. B. RUSH

OIL WELL BARREL

Filed April 16, 1923

By Richard B. Owen,

Attorney

UNITED STATES PATENT OFFICE.

CHARLES B. RUSH, OF KIEFER, OKLAHOMA.

OIL-WELL BARREL.

Application filed April 16, 1923. Serial No. 632,430.

To all whom it may concern:

Be it known that I, CHARLES B. RUSH, a citizen of the United States, residing at Kiefer, in the county of Creek and State 5 of Oklahoma, have invented certain new and useful Improvements in an Oil-Well Barrel, of which the following is a specification.

This invention relates to deep oil wells 10 and water pumps and the primary object of this invention is to provide an improved means for taking care of floating sands in deep wells, so that the pumps will work effectively under these conditions and prevent 15 the clogging up of the working and standing valves.

Another prime object of the invention is to provide a novel sand trap for oil well pumps embodying means for permitting the 20 oil to take a tortuous course through the well casing or liner, so that any sand carried thereby will be deposited in the sand trap provided for the same.

Another prime object of the invention is 25 to provide means for permitting a second standing valve to be quickly and readily dropped into an operative position when the first standing valve becomes leaky or otherwise inoperative.

Another object of the invention is to 30 provide a novel working valve and barrel arrangement, whereby any sand, or the like that may have been carried past the first sand trap will be deposited in a second sand 35 trap, thereby insuring the effective delivering of the oil in a substantially clean condition.

A still further object of the invention is 40 to provide an improved device of the above character, which will be durable and efficient in use, one that will be simple and easy to manufacture and one which can be placed upon the market and incorporated with a deep oil well at a minimum cost.

With these and other objects in view, the 45 invention consists in the novel construction, arrangement and formation of parts, as will be hereinafter more specifically described, claimed and illustrated in the accompanying drawings, in which drawings:

Figure 1 is a longitudinal section through the upper portion of the improved oil well pump.

Figure 1^A is a longitudinal section 55 through the intermediate portion of the improved pump.

Figure 1^B is a longitudinal section through the lower or bottom portion of the improved pump.

Figure 2 is an enlarged fragmentary longitudinal section through the working valve 60 of the pump.

Figure 3 is an enlarged fragmentary section through a portion of the working 65 plunger showing the cups carried thereby.

Figure 4 is an enlarged fragmentary detail section through the lower end of the working plunger showing the type of cup carried thereby.

Figure 5 is an enlarged fragmentary section through the standing valve and cage utilized when the primary standing valve 70 becomes inoperative.

Figure 6 is an enlarged fragmentary section through the primary standing valve.

Referring to the drawing in detail, wherein similar reference characters designate corresponding parts throughout the several views, the letter A generally indicates the improved deep well pump, which embodies the outer casing or liner B. The casing or liner B consists of the working valve portion 10, the secondary standing valve portion 11 and the lower primary standing 80 valve and trap portion 12. The upper portion or section 10 of the casing or lining B has connected thereto a casting 13, while the sections 10 and 11 are connected by the working valve casting 14 and the sections 11 and 12 are connected by the drop valve casting 85 or secondary standing valve casting 15. The lower end of the section 12 has connected thereto a lower casting 16. Disposed within the upper working valve section or portion 10 is a working barrel 20, which is 90 held axially within the portion 10 by means of the working valve casting 14 and it can be seen that the working barrel is threaded into engagement therewith. A bell collar 21 is threaded on the upper end of the working barrel 20 and carries suitable guide or 95 spacing lugs 22 for holding the upper end of the barrel in proper spaced relation to the liner or casing B. It is to be noted that the barrel 20 is arranged in spaced relation 100 to the section 10 of the liner A which forms a sand and sediment trap 23. Reciprocably mounted within the working barrel 20 is the working plunger 25 and it is to be noted that this plunger is of a relatively great length 110 so as to extend substantially the full length of the working barrel and that when the

upper end thereof slides out of the working barrel, the lower end thereof will come into the lower end of the working barrel. As clearly shown in Figures 1 and 14, the working barrel embodies tubes or sections 26 and 27 which are connected together by means of a sleeve 28 that carries a plurality of packing gaskets or cups 29 held in place by suitable retaining rings 30. These gaskets or cups 29 are adapted to frictionally engage the inner surface of the barrel 20 in order to prevent the leakage of the fluid from around the same. The extreme lower end of the section 27 of the working plunger 25 is attached by suitable means a cup or gasket 31 for frictionally engaging the inner surface of the barrel. The upper end of the working plunger 25 also carries a suitable gasket or cup 32 for frictionally engaging the inner surface of the working barrel and the sleeve 33 upon which the cup is mounted supports the working or operating valve 34. This valve 34 embodies a valve seat 35 connected directly with the sleeve 33 and a valve cage 36. A ball valve 37 is employed for fitting upon the seat 35.

Extending axially up into the liner A is the fluid pipe 40 and this pipe is held in place by the lower casting 16 and it is noted that the fluid pipe is spaced from the section 12 of the liner A which forms a sand trap 41. The extreme upper end of the fluid pipe 40 supports the standing valve 42 which will be hereinafter known as the primary standing valve. As shown this standing valve 42 embodies the annular valve seat 43 upon which is adapted to fit the ball valve 44. The ball valve is held in place by means of a suitable valve cage 45. The upper end of this valve cage 45 carries a supporting lug 46 upon which is mounted the filter tube 47. The filter tube 47 is arranged in spaced relation between the fluid inlet pipe 40 and the section 12 of the liner A and has its upper end provided with a head or wall 48, the axial center of which receives the supporting lug 46. The filter tube 47 can be provided with a plurality of openings 49. It is to be also noted at this point that the filter tube 47 terminates short of the lower end of the section 12 of the liner A. Spacing lugs 50 are carried by the lower end of the filter tube so as to maintain the lower end thereof in correct position to the inlet fluid tube 40.

Arranged between the primary standing valve 42 and the working valve 34 is the dropping or secondary standing valve 55. This valve is only brought into use when the primary standing valve becomes leaky or otherwise inoperative. Permanently arranged within the secondary standing valve section 11 of the liner A is a supporting pipe 56 which is threaded into the dropping or secondary standing valve casting 15 and this

supporting pipe carries a sleeve 57 having its upper end flared as at 58 to form a guide for the secondary standing valve 55 when the same is dropped into place. This flared guiding portion 58 can be provided with suitable outlet openings 59 if so desired. The dropping or secondary standing valve embodies a valve seat 60 upon which is adapted to normally fit the ball valve 61 and this valve is retained into position by means of a valve cage 62. The valve seat 60 has connected thereto by means of a suitable coupler 63, a depending sleeve 64 around which is placed suitable cups or gaskets 65 for engaging the inner surface of the sleeve 57 when the said dropping or secondary standing valve is dropped into position. These gaskets or cups are adapted to hold the valve in place. The exterior of the secondary or dropping standing valve 55 at its largest point is of a less diameter than the working valve 25 so as to permit the same to be dropped into position through the said barrel when the primary standing valve becomes inoperative.

In operation of the improved device it can be seen that the working valve and plunger is reciprocated in the ordinary manner through the pump rods (not shown). On the upstroke of the plunger the valve 37 will of course be held on its seat and the fluid will be drawn up by suction through the fluid inlet pipe 40 and unseat the valve 44 of the standing valve structure 42 and will flow down between the fluid pipe 40 and the filter tube 47. The fluid will then flow through the openings 49 and through the lower end of the said filter tube. After which the fluid will be sucked up between the filter tube 47 and the section 12 of the liner A up through the plunger. It is now apparent that as the fluid flows through the opening 49 of the filter tube and begins its upward passage that any sand or sediment carried therewith will be permitted to drop down into the trap 41 and thus the oil or other fluid is relieved of all sediment. Now on the down-stroke of the working valve and plunger the valve 44 of the standing valve structure 42 will be held closed while the valve 37 of the working valve 34 will be unseated which will permit the fluid to flow up through said valve and out of the casting 13 into the oil well pipes. As the fluid flows out of the working valve any sediment, sand or the like that still may be retained therein will be permitted to drop back into the trap 23 provided for that purpose.

Now when the primary standing valve becomes inoperative, it is merely necessary to lift or withdraw the plunger from position and drop the dropping or standing valve 55 in place, after which the same will function as the ordinary standing valve.

From the foregoing description it can be

seen that I have provided an exceptionally simple and durable means for handling oils containing floating sands and the like.

Changes in details may be made without departing from the spirit or the scope of this invention.

What I claim as new is:

1. In a deep well pump, an outer casing, a casting carried by the lower end of the casing, a fluid inlet pipe carried by the casting, a standing valve carried by the fluid inlet pipe, a working plunger including a working valve operatively mounted in the casing above and in spaced relation to the standing valve, a casting arranged between the standing valve and working plunger, and a dropping standing valve adapted to be dropped into the last mentioned casting when the first mentioned standing valve becomes inoperative.

2. In a deep well pump, an outer casing,

a casting carried by the lower end of the casing, a fluid inlet pipe carried by the casting, a standing valve carried by the fluid inlet pipe, a working plunger operatively mounted in the casing above, and in spaced relation to the standing valve, a casting arranged between the standing valve and working plunger, a tube carried by the last mentioned casting, a sleeve associated with the tube, a flared upper guide portion formed on the sleeve, and a dropping standing valve adapted to be dropped into said sleeve including means for frictionally engaging the sleeve to hold the same in place.

In testimony whereof I affix my signature in presence of two witnesses.

CHARLES B. RUSH.
